UNITED STATES PATENT OFFICE.

LEOPOLD F. BURGER, OF RIVERSIDE, ILLINOIS, ASSIGNOR, BY MESNE ASSIGNMENTS,
TO INTERNATIONAL HARVESTER COMPANY, A CORPORATION OF NEW JERSEY.

CARBURETER.

1,395,387.

Specification of Letters Patent.

Patented Nov. 1, 1921.

Application filed April 22, 1918. Serial No. 230,036.

To all whom it may concern:

Be it known that I, LEOPOLD F. BURGER, a citizen of the United States, residing at Riverside, in the county of Cook and State 5 of Illinois, have invented certain new and useful Improvements in Carbureters, of which the following is a full, clear, and exact specification.

This invention relates to carbureters for 10 internal combustion engines.

An object of the invention is to provide a carbureter and water mixer which is compact and can be manufactured at small cost.

Another object is to provide a carbureter 15 which permits the use of two combustible fluids, one, such as gasolene, which is used to start the engine, and another, such as kerosene, upon which the engine may operate after it has become hot.

Another object is to provide means whereby a pump may operate continuously during 20 the operation of the engine to supply a fuel, such as kerosene, to the carbureter, and means whereby this fuel may be caused to flow through the carbureter or be by-passed around it.

These and other objects are accomplished 25 by my invention, which consists of a carbureter including a fuel reservoir, a supply chamber therefor, means for continuously supplying an excess of fuel to the fuel reservoir, and a valve for draining the fuel reservoir or the supply chamber.

Reference is now had to the drawings, in 30 which like characters represent like parts throughout.

Figure 1 is a horizontal section of my carbureter taken on the broken line 1-1 of Fig. 2;

Fig. 2 is a front elevation of the same partly in section on the broken line 2-2 of Fig. 1;

Fig. 3 is a plan view of the carbureter;

Fig. 4 is a vertical section through the 45 auxiliary air valve on the line 4-4 of Fig. 3;

Fig. 5 is a vertical section through the water valve on the line 5-5 of Fig. 3; and

Fig. 6 is a vertical section through the 50 fuel valve on the line 6-6 of Fig. 3.

This carbureter comprises a body 11 containing the fuel reservoir 12, the supply chamber 13, and the overflow chamber 14. The upper part of the body is surmounted by a hooded portion 15 having the air passage 16 partially closed by the auxiliary valve 17, which is pressed by the spring 18, said valve having openings 19 which are always open for the free passage of air. This air passage leads to the downwardly 60 disposed Venturi tube 20, which in turn leads to the inlet valve of the internal combustion engine. Between the supply chamber 13 and reservoir 12 is placed the weir or dam 21, and between the fuel reservoir and the overflow chamber 14 is placed another and lower weir 22. Between the supply chamber 13 and overflow chamber 14 is placed a three-way valve 23, having a longitudinal cavity 25 and a port 24 communicating therewith through the side. Drain passages 28, 29, and 30 lead respectively from the supply chamber, fuel reservoir, and overflow chamber. These passages are all arranged in the same plane with each other and with the 65 port 24 of the rotatable valve 23 so that as the valve is turned it may be brought into registration with any one of these passages. The longitudinal cavity 25 in the valve 23 opens into a passage 26 into which is tapped the overflow pipe 27, which communicates with the main fuel tank of the engine. A fuel supply pipe 31 is likewise tapped into the supply chamber 13, and this pipe communicates with the fuel pump or other 70 source of fuel supply.

At the narrowest portion of the Venturi tube 20 I have placed an opening 32, which may be regulated by means of the needle valve 33. This needle valve is supplied by means of a tube 34 which reaches down into the fuel reservoir 12, the height of fuel in the reservoir being maintained by the weir 22. A water supply opening 35 is placed in the Venturi tube at the same height as the fuel valve, which is likewise regulated by a needle valve 36. This valve is supplied with water through the chamber 37, in which is placed a check valve 38 which normally closes an opening 39 in the threaded plug 100

40. This opening is placed directly over a passage leading to the water jacket in the head 41 of the engine cylinder. This valve is so devised that it will overcome water 5 pressure from the water jacket, and prevent water from flowing into the Venturi tube 20 when the engine is not in operation, but will permit it when the engine is running, due to the vacuum produced in the Venturi tube.
- 10 The carbureter is preferably mounted upon the cylinder head, and fastened by means of cap screws 42. One of these cap screws also carries a spring 43, which serves to prevent the valve 23 from being shaken 15 from its seat and lost. The valve has a handle 23^a, with a projection 23^b, which is adapted to strike stops 11^a in the carbureter body 11, which are so placed as to indicate the two working positions of the valve. The 20 top of the carbureter body also contains two openings 11^b and 11^c, which permit the condition of flow of the fuel to be readily observed, and which also supply a ready means for introducing fuel into the fuel reservoir.
- 25 The manipulation of the carbureter, when starting with a cold engine, is as follows: The water supply valve 36 is first closed, the three-way valve 23 is then turned to the middle position so as to bring the opening 24 30 in registration with the drain 29 to the fuel reservoir. Any fuel then in the reservoir is drained through the passage 26 and the overflow pipe 27 to the main fuel tank. When the fuel reservoir is thoroughly drained the 35 valve 23 is turned so as to bring the port 24 in registration with the opening 28 so as to drain the supply chamber 13, and at the same time to close the fuel reservoir opening into the drain. This is done because I prefer to supply fuel to the supply chamber 13 40 continuously during the operation of the engine, and it is necessary to turn this valve so as to allow this supply of fuel to pass immediately back to the fuel tank, and not allow it to back up and overflow the weir 21 45 into the fuel reservoir 12. With the valve in this position gasoline is introduced through the opening 11^b into the fuel reservoir 12, and the engine started. Enough 50 gasoline is introduced to allow the engine to run until it is thoroughly heated. As soon as that is done, and the supply of gasoline in the fuel reservoir is nearly exhausted, the valve 23 is turned as far in the opposite 55 direction as it will go, or, in other words, until the opening 28 is closed, and the opening 30 from the overflow chamber is brought into registration with the port 24 of the three-way valve.
- 60 It will be understood that in the meantime kerosene, or other fuel, has been continuously supplied to the supply chamber 13, and, as before stated, is allowed to return to the main fuel tank through the overflow 65 pipe 27. The opening 28 now being closed, this fuel will immediately overflow the weir 21 into the fuel reservoir 12, and as soon as this is filled to the height of the weir 22, this heavier fuel will then overflow over the top of this weir in the overflow chamber 14, 70 and thence back through the pipe 27 to the main fuel tank. As soon as the engine has become sufficiently heated to permit, the water valve 36 may be opened, and moisture supplied to the charge received by the cylinder. 75
- What I claim as new is:
1. In a carbureter, a fuel reservoir, means for supplying fuel thereto, means for maintaining the height of fuel therein, and controlling means for draining said reservoir when said controlling means is in one position, and for causing fuel to flow to the reservoir and return excess fuel to the source of supply when said means is in another position. 80
  2. In a carbureter, a fuel reservoir, a supply chamber therefor, means for continuously supplying an excess of fuel to the supply chamber, and a valve for separately draining either the fuel reservoir or the supply chamber. 90
  3. In a carbureter, a fuel reservoir, a supply chamber therefor and an overflow chamber therefor, means for continuously supplying an excess of fuel to the supply chamber, and a valve for separately draining either the fuel reservoir or the supply chamber. 95
  4. In a carbureter, a fuel reservoir, a supply chamber therefor and an overflow chamber therefor, means for continuously supplying an excess of fuel to the supply chamber, and a valve for draining the fuel reservoir, the overflow chamber, or the supply chamber. 100
  5. In a fuel feed means for an internal combustion engine, a fuel reservoir, a supply chamber therefor, an overflow chamber, level maintaining weirs between said chambers and said reservoir, means for constantly feeding fuel to the supply chamber during the operation of the engine, an overflow duct, a valve leading thereto which in one position communicates with the supply chamber, in a second position with the fuel reservoir, and in a third position with the overflow chamber. 110
  6. In a fuel feed means for an internal combustion engine, a fuel reservoir, a supply chamber therefor, an overflow chamber, level maintaining weirs between said chambers and said reservoir, the weir between the supply chamber and the fuel reservoir being higher than the weir between the fuel reservoir and the overflow chamber, means for constantly feeding fuel to the supply chamber during the operation of the engine, an overflow duct, a valve leading thereto which in one position communicates with the sup- 120
  - 65 pipe 27. The opening 28 now being closed, 125

ply chamber, in a second position with the fuel reservoir, and in a third position with the overflow chamber.

7. In a fuel feed means for an internal combustion engine, a fuel reservoir, a supply chamber therefor, an overflow chamber, level maintaining weirs between said chambers and said reservoir, means for constantly

feeding fuel to the supply chamber during the operation of the engine, an overflow 10 duct, and means for draining either the supply chamber, the fuel reservoir, or the overflow chamber to the overflow duct.

In testimony whereof I affix my signature.

LEOPOLD F. BURGER.
